ISAAC THEODORE KAHN, OF CLEVELAND HEIGHTS, OHIO

CONTAINER SEALING DEVICE

Application filed September 17, 1930. Serial No. 482,470.

My invention consists in a new type of sealing member to be used in connection with a container, as an example of which I have selected a metal oil barrel such as is commonly used by oil refining companies in the distribution of their products to wholesalers and retailers, together with the means of attachment of such sealing member. In such distribution of oil products it is necessary to use such sealing members for the purpose of identifying the products of a particular company and to prevent substitution of any other product for that of the company.

The structure of such sealing members is of light material, such as sheet metal, and there is placed thereon the name of the company whose products are in the container sealed. This seal should be destroyed and will always be destroyed in the process of removal, when drive screws are used, as I hereinafter point out. As at present employed in the oil industry, whose containers I have selected for the purpose of explaining my invention, the sealing members are manufactured in a variety of shapes and sizes made necessary by the corresponding variety of shapes and sizes of the plugs in said containers to which the sealing members must be attached. This variety in style of the sealing members is largely due to the means of attaching them now employed because of the structure of the sealing member. As at present manufactured there is no device for attaching the sealing members other than that of bending the flanges or sides or lower edges of the sides inwardly after the sealing member is placed over and around the plug hereinafter illustrated. To do this it is necessary to somehow bend the flanges of the sealing member around the top of the barrel plug, or into undercuts made for the purpose, with which some plugs are provided.

To properly affix the sealing member in such fashion is by no means convenient and requires considerable time.

All this inconvenience in the manner of attaching the sealing member is overcome by my proposed invention hereinafter de-

scribed in detail. Briefly it consists of employing a type of sealing member in which is punched one or more small holes so designed as to accommodate an ordinary drive screw and to be used in combination with the plug in the container, hereinafter styled oil barrel or barrel, which also has one or more small holes so placed as to accommodate the small drive screw or screws which are first driven through the corresponding holes in the sealing member when it is placed over the upper surface of the barrel plug. One or at the most several light taps with an ordinary hammer on the drive screw after the screw is placed in the hole in the upper surface of the sealing member will suffice to drive the screw into the hole in the upper surface of the barrel plug, firmly securing the sealing member to the plug and thus doing away with all need for bending in the flanges of the sealing member around the plug, such as is now necessary. One screw is enough as the hole or holes in the barrel plug are preferably close to the center.

Such means of attaching the sealing member has the additional advantage that it obviates the necessity of making a different shape of sealing member for every size and shape of container plug, for the reason that in my plan of sealing it is unnecessary for the flanges of the sealing member to fit snugly around the sides of the barrel plug as is necessary under present means of attachment, for the drive screw through the hole or holes in the sealing member over plug serves to keep the seal firmly attached irrespective of the proximity and general fit of the sealing member with the barrel plug. Although the width or circumference of the plug may vary, the distance it protrudes above the surface of the barrel is practically uniform in all cases, and the lower edges of the flanges of the sealing member would therefore reach to the surface of the barrel immediately around the barrel plug, irrespective of the width or circumference of the plug.

Furthermore, under the customary means at present employed of bending the flanges

of the sealing member, it is exceedingly difficult to insert a screw driver, knife, or other implement between the flanges of the member and the side of the plug, in order to pry loose and lift the sealing member. Consequently, it is now often necessary to employ some such means as a can opener and to work from the upper surface of the sealing member in order to remove it. Under 10 my arrangement, knife, screw driver, etc., may be readily inserted under the flanges of the sealing member, and it pried off, the bending or destruction being highly desirable so that the seal cannot be again used 15 in any event. To the accomplishment of the foregoing and related ends, said invention, then, consists of the means hereinafter fully described and particularly pointed out in the claims.

20 The annexed drawing and the following description set forth in detail certain mechanism embodying the invention, such disclosed means constituting, however, but one of various mechanical forms in which the 25 principle of the invention may be used.

In said annexed drawing:—

Fig. 1 is a perspective view of the container; Fig. 2 is a plan view in cross section showing the upper portion of the oil barrel 30 including the bung which is plugged and the plug sealed, the seal and plug embodying my invention; Fig. 3 is a plan view of the upper surface of the plug and the upper surface of the sealing member; Fig. 4 is 35 the ordinary type of drive screw; and Fig. 5 is a cross section embracing a portion of the top of the seal with the screw in place as when sealed.

In Fig. 2, there is shown a container, here 40 represented as a metal oil barrel 10 provided with a threaded opening 13 in the side or top of the barrel, into which fits the threaded plug 12 of the barrel. The upper portion 12A of the plug 12 protrudes when the 45 plug is screwed into the barrel, which protruding portion of the plug extends horizontally beyond the threaded opening of the barrel and which is round, square, or hexagon in shape. The upper surface of this 50 part 12A of the plug is flat, and has a square hollow center 19 for the insertion of a wrench to remove the plug from the barrel opening. The wrench cannot be inserted 55 without the destruction or mutilation of the sealing member.

In this upper surface of 12A of the plug, around the hollow center 19 are drilled the small hole or holes 16, as shown in Fig. 3, preferably so spaced as to be at about the 60 center of the upper surface; that is to say, between the outer edge of the upper surface of 12A and the hollow center 19, but closer to the edges of a hollow center 19, than the outer edges of 12A. This enables one drive 65 screw to securely fasten the sealing member.

The hole or holes 16 are unthreaded for the reception of the drive screw 17, as shown in Fig. 1 and Fig. 3.

The seal 14 is constructed of a light weight 70 sheet metal, and is of a size slightly larger than the protruding portion 12A of the plug, so that it will cover the plug and its flange 18 be approximately perpendicularly parallel to the sides of 12A, and extend to the surface of the barrel immediately surrounding the plug 12. As above pointed out, it is unnecessary to have the flange fit snugly around 12A in my invention, as the screw means of attachment is independent 75 of the flange or fit of the sealing member. In the sealing member there is a small hole or holes 15, as shown in Fig. 3, arranged and located in a similar style as the hole or holes 16 in the upper surface of the plug, so that when the seal 14 is placed 80 over the portion 12A of plug 12, the small hole or holes 15 coincide exactly with hole or holes 16. For fastening, the drive screw or screws 17 are then placed in holes 15 and driven through into 16. As before mentioned, the whole series of holes may be used or only one, leaving the other holes 16 untouched and in condition for future use if desired by the sealing company, as is often the case. The centering of holes 15 and 16 85 enables one ordinary drive screw to do the work now done only by a laborious inturning of flange 18 of the sealing member. On the other hand, if the manufacturer is certain he will not use the container again, 90 there may be only one hole in the plug to guarantee against future use.

Other modes of applying the principle of my invention may be employed instead of the one explained, change being made as 105 regards the mechanism herein disclosed, provided the means stated by any of the following claims or the equivalent of such, be employed.

I therefore particularly point out and distinctly claim as my invention:

1. A metal container having a relatively small outlet, metallic closure-means therefor, a sheet-metal sealing member superposable over and encompassing said closure-means and of a shape to be destroyed on applying a removing-wrench to the closure-means, and securing means for said sealing member drivable therethrough into the metal beneath.

2. A metal container having a relatively small outlet, a metal plug for closing such outlet, a sheet-metal sealing member superposable over and encompassing said closure-means and of a shape to be destroyed on applying a removing-wrench to the closure-means, and securing means for said sealing member drivable therethrough into the metal beneath.

3. A metal container having a relatively 130

- small outlet, a metal plug for closing such outlet, a sheet-metal sealing member superposable over and encompassing said closure-means and of a shape to be destroyed on applying a removing-wrench to the closure-means, and securing means for said sealing member having steep spiral threads and being drivable through the sealing member into the metal beneath.
4. A metal container having a relatively small outlet, a metal plug therefor having a wrench-hold, a sheet-metal sealing cap for covering and encompassing the wrench-hold and plug and of a shape to be destroyed on applying a removing-wrench to the plug, and securing means for said cap having steep spiral threads and being drivable through the cap into the plug.

Signed by me, this 15th day of September, 1930.

ISAAC THEODORE KAHN.
